UNITED STATES PATENT OFFICE.

PAUL HALLOT, OF VINCENNES, FRANCE.

RAILWAY-BRAKE.

SPECIFICATION forming part of Letters Patent No. 784,489, dated March 7, 1905.

Application filed July 7, 1902. Serial No. 114,700.

To all whom it may concern:

Be it known that I, PAUL HALLOT, a citizen of France, residing at Vincennes, France, have invented certain new and useful Improvements in Railway-Brakes, of which the following is a specification.

This invention relates to certain improvements in the railway-brakes for which I obtained Letters Patent Nos. 689,716 and 733,838 and which improvements are hereinafter fully described with reference to the annexed drawings, in which—

Figure 1 represents a balancing-valve applicable to all brakes operated by differential action (Wenger type) and adapted to be employed instead of the valve 24 described in the specification of my above-mentioned patent, No. 733,838. Fig. 2 shows a modification of this balancing-valve. Fig. 3 shows the said balancing-valve applied more particularly to the winch or drum-brake described with reference to Fig. 1 of Patent No. 689,716. Fig. 4 shows a modification of the arrangement represented in Fig. 3. Fig. 5 shows a modification of the arrangement for regulating the skidding pressure in distributing-brakes, (Westinghouse, &c.)

Referring to Figs. 1 and 2, it will be understood that the brakes of the train are applied by exhausting pressure from between the pistons *m* *n*. The application of the brakes brings the friction device *o* into contact with the car-wheel, as will be understood by inspecting Fig. 2 of my Patent No. 733,838. When the friction device *o* contacts with the car-wheel, the cord *p* is wound thereupon, and the lever *q* and connected piston *c* in cylinder *d* consequently are moved to the right, which action causes air to be compressed in the right end of the cylinder *d* and to be forced into the outer ends of the brake-cylinder through the pipes *t*. This increase of pressure in the outer ends of the brake-cylinder forces the pistons *m* *n* closer together and more strongly applies the brakes, as will be understood.

The balancing-valve or auxiliary cylinder, Fig. 1, which can be used in substitution of the valve 24 shown in Fig. 1 of my Patent No. 733,838, consists of a conical plug *a*, the stem

or rod *b* of which traverses the piston *c* and establishes communication between the two ends or chambers of the cylinder or air-compressor *d* when the valve is raised from its seat. This stem or rod *b* is controlled by a small piston *e*, sliding with slight friction in the chamber or cylinder *f*, which is arranged parallel with the axis of the rod of the piston *c*. A small compression-spring *g* keeps the plug *a* down on its seat when equal pressure prevails in both ends or chambers of the cylinder *d*. The area of the small piston *e* is such that the plug *a* is forced to quit its seat so soon as a certain excess of pressure occurs in that portion of the chamber or cylinder *f* communicating with the main conduit or train-pipe *h*. The purpose of this balancing-valve is to prevent partial sliding of the vehicle-wheel on the rail when the skidding pressure is attained. In fact, when this maximum of pressure is obtained the speed of the wheel will immediately tend to decrease; but at the same time the sudden compression of the air by the piston *c* reacts so as to destroy the equilibrium and to return the piston toward the left. Now as the port *i*, through which the cylinder *f* communicates with the main conduit or train-pipe *h*, is very small the piston *e* is not able to move so quickly toward the left as the piston *c*. A portion of the compressed air from the brake-cylinder therefore flows to the rear of the piston *c*, the pressure on the brake-blocks decreases, and the wheel is constrained to preserve the speed of rotation corresponding to the movement of the train. When the skidding pressure is again attained, the same phenomenon is reproduced, the piston *c* moving backward each time a little more toward the left of the cylinder *d*, which thus realizes the mechanical criterion of the decreasing scale of the skidding pressures.

The balancing-valve instead of being connected directly to the main conduit *h* by the pipe *j* may be connected directly to the brake-cylinder by the pipe *k*, Fig. 2, which leads into the space between the two large pistons *m* and *n*. In this way the fall of pressure effected by the displacement of the piston *c* toward the right resulting from the working of the governor produces its effect directly in

the chamber common to these two pistons, and thereby increases in proportion the air-pressure on the other face of these pistons, and hence the power of the brakes of each vehicle. The purpose and the operation of the balancing-valve, however, remain identical.

10 In order to reduce the expenditure of air to a minimum, the capacity of the cylinder *d* may be reduced proportionally to the load of the vehicle. To this end the cable *p* (of the drum of the governor) terminates in four hooking-links *y*, capable of engagement with the lever *q* and corresponding, respectively, with loads of five, ten, fifteen, and twenty tons. The stroke allowed to the piston *c* and the capacity of the cylinder *d* can thus be increased according to the load carried. This arrangement is, moreover, applicable to all systems of brakes.

20 Fig. 3 shows the application of the same balancing-valve to the winch or drum-brake forming the subject of my aforesaid patents. The pipe *t*, which connects the cylinder *d* with the chamber wherein the pressure is utilized, opens in this case in the space between the two pistons *r* and *r'*, and the pipe *k* opens under the piston *r*.

Fig. 4 shows a simplified form of the previous arrangement. The piston *r'* is here dispensed with and the lever *s* is raised by a spring *z*, fixed to the underframing. This figure also shows another way of applying the friction-roller *o* to the wheel-tire. Said friction-roller is held away from the wheel-tire by means of a suitable elastic device 2. Through the arm 3 the rod *u* of the operating-piston *r* passes freely, and a stop-nut 4, adjustably arranged on the piston-rod, moves it in opposition to the elastic device 2 when the decrease in pressure produced by the engineman reaches a predetermined degree. The drum of the governor will therefore not come into operation on the application of moderate braking action; but it will be the more energetic as the fall of pressure produced by the engineman is the stronger. This action may besides be combined with that of the spring *v* by interposing between the nut 4 and the arm 3 a suitable spiral spring.

50 Fig. 5 shows a modification of the arrangements applicable to brakes fitted with distributors, (Westinghouse, &c.) Its object is to isolate or cut off the brake-cylinder 7 from the auxiliary reservoir 8 during the working of the automatic governor so that the air compressed by the working of this latter can be entirely utilized to increase the effective pressure on the pistons 9 and 10. To this end the pipe 11, conveying the air from the auxiliary reservoir 8 to the brake-cylinder 7, is provided with a retaining clack-valve 12, which closes all communication with said reservoir 8 immediately the compressor comes into action. The principle of the working of the triple valve 13 remains the same. However, to ex-

haust the air from the cylinder 7 at the moment of releasing the brake the pipe 14, which connects said cylinder with the compressor *d*, is fitted with a branch pipe 15, which corresponds to the usual pipe which leads from the triple valve to the cylinder 7. Therefore it is through the pipe 15 that the exhaust of the air from the two cylinders 7 and *d* is effected at the moment of releasing the brake, and this so much the more rapidly as the pressure on the left face of the piston *c* of the compressor happens to be the more or less preponderant. For this purpose the triple valve is slightly modified—that is to say, the pipe 11 from the cylinder is so arranged as to open into the valve a little above the pipe 15. In order to avoid any slipping, even partial, of the vehicle-wheel when the skidding pressure is attained, the piston *c* is provided with a very small hole 16, through which air is free to pass to the left of the piston *c*, so causing the pressure in the cylinder *d* to decrease progressively.

Having now particularly described and ascertained the nature of my said invention and in what manner the same is to be performed, I declare that what I claim is—

1. In a fluid-pressure brake, the combination of a train-pipe, a brake-cylinder, a piston in said brake-cylinder, an air-compressor connected with said brake-cylinder, a piston in said air-compressor, a frictional device adapted to be placed in contact with a movable part of the vehicle, said frictional device being connected with the piston of said air-compressor, and means for establishing communication between the opposite ends of said air-compressor. 95

2. In a fluid-pressure brake, the combination of a brake-cylinder, a piston in said brake-cylinder, a train-pipe connected with said brake-cylinder on one side of said piston, an air-compressor connected with said brake-cylinder on the opposite side of said brake-piston, a piston in said air-compressor, a frictional device adapted to be placed in contact with a movable part of the vehicle, said frictional device being connected with the piston of said air-compressor, and means for establishing communication between the opposite ends of said air-compressor. 105

3. In a fluid-pressure brake, the combination of a brake-cylinder, a piston in said brake-cylinder, a train-pipe connected with said brake-cylinder on one side of said piston, an air-compressor connected with said brake-cylinder on the opposite side of said piston, a piston in said air-compressor, a friction-pulley adapted to be placed in contact with a movable part of the vehicle, a flexible element adapted to be wound on said friction-pulley, 115 said flexible element being connected with the piston of said air-compressor, and means for establishing communication between the opposite ends of said air-compressor. 120

4. In a fluid-pressure brake, the combination 125

of a brake-cylinder, a piston in said brake-cylinder, a train-pipe connected with said brake-cylinder on one side of said piston, an air-compressor connected with said brake-cylinder on the opposite side of said piston, a piston in said air-compressor, a frictional device adapted to be placed in contact with a movable part of the vehicle, said frictional device being connected with the piston of said air-compressor, an auxiliary cylinder connected with said air-compressor, a piston in said auxiliary cylinder, the stem of said piston being conically enlarged and passing through the piston of said air-compressor, and a connection between said auxiliary cylinder and the train-pipe system of the train.

5. In a fluid-pressure brake, the combination of a brake-cylinder, a piston in said brake-cylinder, a train-pipe connected with said brake-cylinder on one side of said piston, an air-compressor connected with said brake-cylinder on the opposite side of said piston, a piston in said air-compressor, a lever connected with the piston of said air-compressor, a flexible element connected with said lever, a friction-pulley adapted to be placed in contact with a movable part of the vehicle, said flexible element being adapted to be wound on said frictional pulley, an auxiliary cylinder connected with said air-compressor, a piston in said auxiliary cylinder, the stem of said piston being conically enlarged and extending through a conical aperture in the piston of said air-compressor, and a communication between said auxiliary cylinder and said train-pipe.

6. In a fluid-pressure brake, the combination of a brake-cylinder, a pair of pistons in said brake-cylinder adapted to operate in opposite directions, a train-pipe connected with said brake-cylinder between the pistons therein, an air-compressor, a communication between said air-compressor and each end of said brake-cylinder, a piston in said air-compressor, a lever

connected with the piston of said air-compressor, a flexible element connected with said lever, a friction-pulley adapted to be placed in contact with a movable part of the vehicle, said flexible element adapted to be wound on said friction-pulley, an auxiliary cylinder connected with said air-compressor, a piston in said auxiliary cylinder, the stem of said piston being conically enlarged and extending through a conical aperture in the piston of said air-compressor, and a communication between said auxiliary cylinder and said train-pipe.

7. In a fluid-pressure brake, a compressor comprising a cylinder and a piston, for automatically increasing the fluid-pressure by which the brakes are applied, and means for automatically establishing communication between the opposite ends of said compressor to reduce the pressure on the brakes according to the reduction of the rotary speed of the wheels.

8. In a fluid-pressure brake, a compressor comprising a cylinder and a piston, for automatically increasing the fluid-pressure by which the brakes are applied, and a balancing-valve for automatically establishing communication between the opposite ends of said compressor to reduce the pressure on said brakes.

9. In a fluid-pressure brake, a compressor comprising a cylinder and a piston, for automatically increasing the fluid-pressure by which the brakes are applied, and a balancing-valve comprising an auxiliary cylinder and piston for automatically establishing communication between the opposite ends of said air-compressor to reduce the pressure on said brakes.

In testimony whereof I have hereunto set my hand in presence of two subscribing witnesses.
